UNITED STATES PATENT OFFICE.

GIOVANNI EMANUELE ELIA, OF NEW YORK, N. Y.

APPARATUS FOR DESTROYING SUBMARINE BOATS.

1,309,120.

Specification of Letters Patent.

Patented July 8, 1919.

Application filed July 31, 1917. Serial No. 183,665.

To all whom it may concern:

Be it known that I, GIOVANNI EMANUELE ELIA, a subject of the King of Italy, residing at the Hotel Ritz-Carlton, New York city, in the county of New York, State of New York, have invented certain new and useful Improvements in Apparatus for Destroying Submarine Boats; and I do hereby declare the following to be a full, clear, and exact description of the invention, such as will enable others skilled in the art to which it appertains to make and use the same.

This invention is directed to the provision of an apparatus for destroying submarine boats and involves the use of a barrier adapted to be placed in position in the sea where it may be engaged by a submarine boat and a mine associated with the barrier and provided with automatic firing mechanism such that when the barrier is engaged and ruptured by a submarine boat the mine will be automatically exploded.

It has been proposed heretofore to place nets in the sea where they may be engaged by a submarine boat, the net being relied upon to arrest the boat or having automatic signaling devices associated with it such that when the net is propelled through the water by a submarine boat, the signaling devices will be actuated automatically to indicate the fact that the net has been engaged. The utility of such nets, whether they are provided with the signaling devices or not, is greatly decreased if the submarine boats are able to disengage themselves from the nets, as by being provided with cutting devices which sever the cables of the net.

The present invention contemplates the use of a barrier which is intended to be broken by the submarine boat and involves the application of charges of an explosive and firing devices therefor which are automatically operated when the barrier is broken. The barrier may be in the form of a single cable which is positioned by means of suitable anchoring devices below the surface of the sea and across a path which is apt to be traveled by submarine boats. A single cable may be employed or two or more cables may be arranged one below another. The charges of the explosive are connected to this cable and the automatic firing mechanisms therefor are under the control of the cable so that when the cable is broken, the firing mechanism is set in operation. Each mine

preferably consists of a casing containing the explosive, a float which is normally held submerged by the cable, and a firing mechanism for the explosive actuated by the float, the breaking of the cable being arranged to release the float so that it at once rises in the water due to its buoyancy and by its upward movement operates the firing mechanism. The firing mechanism may be actuated by a reel on which a cable is wound, the other end of the cable being connected to the float so that the ascent of the float causes rotation of the reel and thereby actuates the firing mechanism.

The invention will be readily understood by reference to the following description taken in connection with the accompanying drawings, in which Figure 1 is a diagrammatic view of one embodiment of the invention; Figs. 2 and 3 are views similar to Fig. 1 illustrating slight modifications of the construction illustrated in Fig. 1; Fig. 4 is a central sectional view of the charge and its firing mechanism; Fig. 5 is a view in elevation showing the float held in its normal position on the mine casing by the cable; and Figs. 6, 7, 8 and 9 are detail sectional views showing features of construction which may be employed in the construction of the mine and the cable.

Referring first to Fig. 1, the cable which constitutes the barrier adapted to be engaged and broken by a submarine boat is indicated at 10. It is held in position submerged below the surface of the sea by means of suitable anchoring devices. These may consist of cables 11 connected at their upper ends to the horizontal cable 10 and at their lower ends to anchors 12. When the anchoring devices 11 consist of flexible cables, these may extend up to the surface of the sea and have buoys 13 connected to their upper ends, the function of which is to maintain the horizontal cable 10 at the selected depth and in a horizontal position. If desired, when the depth of the water permits, the anchoring devices 11 may consist of long poles driven into the sea bed and having the horizontal cable 10 affixed thereto.

Between each pair of adjacent anchoring cables or poles 11 is a mine or a plurality of mines, each provided with a firing mechanism which is automatically operated when the cable 10 is broken. Each mine preferably consists of a casing 14 for the ex-

plosive and a float 15 normally held together by the cable 10, and an automatic firing mechanism for the charge of explosive in the casing 14 actuated by the upward movement of the float 15 when it is released from the cable 10. The section of the cable 10 at the right of Fig. 1 is shown as broken by a submarine boat 16. Its breakage results in release of the float 15 from the casing 14 and the upward movement of the float 15 to or toward the surface of the sea causes actuation of the firing mechanism for the charge in the casing 14 by drawing out a cable 17 from the casing 14 and thus actuating the firing mechanism within the casing. The casing 14 and float 15 are normally held together by having the cable 10 pass through openings in overlapping portions of these two parts and when the cable 10 is broken by the boat 16, the end of one of the two parts of the broken cable is drawn out of the opening in these two parts by its own weight so as to release the float from the casing. The breakage of the cable 10 would usually occur at the point where the cable is engaged by the stem or other portion of the submarine boat.

Fig. 2 indicates a modification of the construction indicated in Fig. 1 consisting in the provision of means for determining at what point the cable 10 will break, so as to effect the release of the float 15 more reliably and with less chance of a delay which might result in allowing the submarine boat 16 to proceed on its course out of the range of the charge in the casing 14 before the charge is exploded. In the Fig. 2 construction the cable 10 is weakened at two points, indicated at 18, on opposite sides of and close to the mine. For this purpose the cable 10 may have sections 18 of relatively soft metal inserted therein so that when the cable is subjected to strain by being engaged by a moving submarine boat, the cable will part at one of these two weakened sections, leaving but a short end of the cable to be withdrawn from the mine in order to release the float from the casing for the explosive charge.

In Fig. 3, but a single weakened portion is provided in each length of the cable 10 between a pair of adjacent anchors 11, and this single weakened portion is at the point where the cable passes through the openings in the mine as shown at 19. In other respects the constructions shown in Figs. 2 and 3 are like that shown in Fig. 1. Fig. 4 illustrates the construction which I prefer to employ for the mine. In this figure the casing for the explosive charge is shown at 14 and the float at 15. Within the casing 14 is a central tube containing the primer 20 and directly above this is the firing pin 21 carried by a vertically movable head 22. Within an upper compartment of the casing

14 is a reel 23 mounted for rotation on the central tube of the casing. This reel has a cable 24 wound thereon and the free end of the cable is connected to the float as shown at 25. Near the end which is connected to the float, the cable 24 is connected to a pin 26 which passes through an arm 27 on the casing 14 and enters an opening in a block 28 which is secured to the reel 23. When in the position shown, the pin 26 prevents rotation of the reel 23; when the float 15 is detached from the casing and begins to rise, the first part of the upward movement causes withdrawal of the pin 26 from the block 28 so as to free the reel for rotation and thereafter the drawing off of the cable from the reel 23 by the upward movement of the float causes rotation of the reel.

The hub 29 of the reel is extended upwardly and near its upper end is interiorly threaded to coact with a threaded tube 30, the lower end of which is contracted somewhat to form an interior shoulder adapted to engage a head on a rod 31 which lies within the tube. The lower end of this rod is exteriorly threaded and engages threads on the interior of a shaft 32. The lower end of this shaft is provided with a circumferential groove, the walls of which are inclined, and this end of the shaft is adapted to fit within an opening in the head 22 for the firing pin 21. In the head 22 are two diametrically opposite openings or keyways adapted to receive keys 33, the ends of which are tapered. A coiled spring 34 lies between the head 22 and an internal shoulder on the central tube of the casing and normally this spring is not under tension. The construction of these parts is such that when the reel 23 is rotated by the drawing off of the cable 24 therefrom, the coacting threads on the hub 29 of the reel and the tube 30 cause upward movement of the tube; when the tube is thus moved upward, the shoulder thereon engages the lower end of the head on rod 31 so that thereafter the rod moves with the tube and as the rod moves upward, it carries with it the shaft 32 and head 22, resulting in compression of the spring 34. When the upward movement of these parts has continued so far that the outer ends of the keys 33 come opposite a circumferential groove 35 on the interior wall of the tube of the casing, the keys 33 move outwardly, due to the tapered coaction of the interior ends of the keys with the circumferential groove in the lower end of the shaft 32. This outward movement of the keys 33 projecting their ends into the groove 35 releases the head 22 from the shaft 32 and the head is then driven downward forcibly by the expansion of spring 34 driving the firing pin 21 into the primer 20 and exploding the charge within the casing 14. The threaded con-

nection of the rod 31 to the shaft 32 affords a ready means for adjusting the apparatus for firing the charge after the desired length of the cable 24 has been drawn off from the reel 23; by turning the rod 31, the distance through which the tube 30 must be raised before it engages the head of the rod 31 may be regulated as desired.

The upper portion of the compartment at 10 the top of the casing for the reel 23 consists of arms 36 secured at their upper ends to a tube 37 which extends upwardly a substantial distance in continuation of the central tube of the casing proper. This tube 15 37 passes through a central opening in the float 15 and extends beyond the top wall of the float. In the projecting end of the tube 37 is a transverse opening. It is 20 through this opening that the cable forming the barrier extends to normally hold the float and the casing for the explosive charge together. Fig. 5 shows the end of the tube 37 projecting above the upper end of the float 15 and the cable 10 passing through 25 the transverse opening in tube 37. These same parts are shown in section in Fig. 6. If desired, the construction employed at the upper end of tube 37 may be such as to facilitate the movement of the broken end 30 of the cable 10 through the transverse opening in tube 37 so as to release the float from the casing for the explosive. Thus, in Fig. 8, the upper end of the tube 37 is shown as having a roller 38 mounted therein and 35 on the top of the float 15 two similar rollers 38 are mounted. The cable 10 passing through the transverse opening in the tube 37 is engaged on one side by the roller 38 within the tube and on the other side by 40 the two rollers 38 mounted on the float. These rollers turn freely so that when the cable 10 is broken, the resistance to movement of the broken end of the cable out through the transverse opening in tube 37 45 is minimized.

Figs. 7 and 8 show one construction which may be utilized in weakening the cable 10 at the points 18 and 19 of Figs. 2 and 3. In Figs. 7 and 8, the cable 10 is shown as having a section 39 of metal therein provided at its central portion with a circumferential groove such that the strength of the cable at this groove is less than at any other point. Metal inserts 39 may be provided in the cable 10 on opposite sides of the tube 37, as indicated in Figs. 2 and 8, or a single such insert may be provided at the point 19 where the cable 10 passes through the tube 37. Another construction which may be employed is indicated in Fig. 9 where the ends of the cable 10 are secured to metal pieces 40 which fit together by a tongue and groove-connection, and a pin 41 passes transversely through the overlapping parts of the tongue and groove. When this construction

is employed, the straining of the cable 10 results in shearing of the pin 41 and the ends of the severed cable are drawn out of the transverse opening in the tube 37 so as to release the float from the mine casing.

The construction described therefore involves the combination of a barrier adapted to be positioned in the sea below the surface so that it may be engaged and broken by a submarine boat, and a charge of explosive provided with an automatic firing device which is actuated when the barrier is broken by having the breakage of the barrier release a float whose ascent under its own buoyancy operates the firing gear of the explosive charge. The anchoring cables for the horizontal cable which is to be broken by the submarine boat may be placed as close together as conditions warrant and a mine placed between each pair of anchoring cables. If desired, cables 10 may be provided at different depths and a mine may be connected to each one of the several parallel cables. When the cable is broken and the float thereby released, the ascent of the float takes place quickly so that the firing of the explosive charge occurs after such a short interval of time as to preclude the possibility that the submarine boat will have proceeded on its way far enough to be out of the zone of danger.

I claim:

1. Apparatus for destroying submarine boats comprising the combination of a barrier of substantial length adapted to be anchored in the sea extending between substantially fixed points in position to be engaged by a submarine boat, an explosive charge connected to the barrier, a firing mechanism for the charge and means for maintaining the firing mechanism normally under tension to operate it to fire the charge, said firing mechanism being normally held against operation by the anchored barrier whereby when the barrier is broken by being engaged by a submarine boat the firing mechanism is released and is operated by said force to fire the charge.

2. Apparatus for destroying submarine boats comprising the combination of a barrier adapted to be submerged in the sea in position to be engaged by a submarine boat, an explosive charge, a firing mechanism therefor, and a float for operating the firing mechanism held submerged by the barrier and released when the barrier is broken.

3. Apparatus for destroying submarine boats comprising the combination of a barrier adapted to be submerged in the sea in position to be engaged by a submarine boat, a casing containing an explosive and a float held together in a submerged position by the barrier and released from each other when the barrier is broken, and a firing mechanism for the explosive in the casing connect-

ed to the float and operated thereby when the float is released from the casing; substantially as described.

4. Apparatus for destroying submarine boats comprising the combination of a barrier adapted to be submerged in the sea in position to be engaged by a submarine boat, a casing containing an explosive, a firing mechanism for the explosive including a reel 10 which operates the firing mechanism when it is rotated, a float which with the casing is held submerged by the barrier the breaking of the barrier operating to release the float to permit it to rise in the water, and a cable 15 connected at one end to the float and wound on said reel; substantially as described.

5. Apparatus for destroying submarine boats comprising the combination of a cable

adapted to be submerged in the sea in position to be engaged by a submarine boat, a 20 casing for an explosive charge having a tubular extension thereon, an annular float through which the tubular extension passes, the end of the tubular extension beyond the float being provided with a transverse opening through which the cable extends, a firing mechanism for the explosive charge, and a connection from the float to the firing mechanism through which the float operates the firing mechanism when the float ascends 25 in the water after being released from the casing by the withdrawal of the cable from the transverse opening in said tubular extension; substantially as described.

In testimony whereof I affix my signature. 30
GIOVANNI EMANUELE ELIA. 35
